(57) **CLAIM**

The ornamental design for a rear body panel for motor vehicle, as shown and described.

DESCRIPTION

FIG. 1 is a perspective view of a rear body panel for motor vehicle according to a first embodiment showing my new design;

FIG. 2 is a front view thereof;

FIG. 3 is a right view thereof;

FIG. 4 is a left view thereof; and

FIG. 5 is a top view thereof.

FIG. 6 is a perspective view of a rear body panel for motor vehicle according to a second embodiment showing my new design;

FIG. 7 is a front view thereof;

FIG. 8 is a right view thereof;

FIG. 9 is a left view thereof; and,

FIG. 10 is a top view thereof.

The significantly darker portions of the rear body panel for motor vehicle in the center represent a contrast in color from the surrounding significantly lighter portions of the rear body panel for motor vehicle.
